OIL CAN

Application filed September 7, 1928. Serial No. 304,517.

My present invention has reference to improvements in oil cans for dispensing lubricating oil or like material and has for its primary object the provision of an oil can of the force pump type adapted for use with machinery of any character and which may be made to positively deliver oil when desired, regardless of the position of the oil.

To the attainment of the above broadly stated objects and others which will present themselves as the nature of the invention is better understood, the improvement also resides in many other novel features of construction, combination and operative association of parts, one satisfactory embodiment of which is disclosed by the accompanying drawings.

In the drawings:

Figure 1 is an approximately central vertical longitudinal sectional view through an oil can in accordance with this invention.

Figure 2 is a sectional view approximately on the line 2—2 of Figure 1, looking in the direction of the arrows.

The body of the can 1 of my improved oiler is in the nature of a cylinder which is closed at both of its ends, and has one of its sides provided with a handle 2 whose top is formed with an extension 3 that affords a thumb or finger hold. The closed top of the can is provided at one side of the center thereof with an opening surrounded by an outwardly extending flange, the said opening affording an oil inlet to the can and the same is normally closed by a screw cap 4. The top of the oiler 1, at the center thereof is provided with another opening that is surrounded by an outwardly directed threaded sleeve 5 and on this sleeve there is screwed a packing nut 6.

Passing through the packing in the nut 6 and through the sleeve 5 there is the straight spout 7 of the improvement. The spout has secured on its inner end a disc 8, and the said disc has fixed on its inner face, adjacent its outer periphery a compressible gasket or a washer 9 which contacts with the inner wall or bore of the can 1. The disc 8 is formed with an opening 10 and this opening is normally closed by a valve 11 that is formed by

enlarging one end of a spring strip 12, the second end of the said strip being otherwise secured by means 13 to the disc 8. Obviously the disc 8 and the gasket or compressible ring member 9 provide the spout 7 with a plunger.

Freely received on the spout 7, outward of the can 1 there is a slidible block 14. This block is influenced in one direction by a spring 15, which surrounds the spout and contacts with the inner face of the block and the outer face of the packing nut 6.

Arising from the top of the can 1 there is a bracket 16. Pivoted to this bracket, as at 17, there is a lever 18 that has one of its ends rounded, as at 20, and its second end offset, as at 21. The offset end 21 is directed toward the block 14 and there is pivoted to this end of the lever a link 22. This link is pivoted to a dog 23. The dog in turn is pivoted, as at 24, in a depression or pocket 25 in the block 14. The active end of the dog is designed to have its lower edge contact with the spout 7.

The spring 12 is not of sufficient strength to prevent opening of the valve 11 when the can 1 is filled with oil, so that a certain quantity of such oil will be delivered through the opening 10 below the plunger. When the oil is to be forcibly ejected from the can, the operator gripping the handle 2, arranges his thumb against the thumb piece 3 of the said handle and his forefinger in the ring 20 of the lever 18, drawing the lever toward the handle 2, thereby canting the dog 23 to cause the same to grippingly engage with the spout to force the spout and the plunger attached thereto downwardly in the can, thereby compressing the oil between the plunger and the bottom of the can to cause such oil to be forcibly ejected through the spout 7.

The simplicity of the construction and the advantages thereof will, it is thought, be understood and appreciated by those skilled in the art but obviously I do not wish to be restricted to the precise details herein set forth and, therefore, hold myself entitled to make such changes therefrom as fairly fall within the scope of what I claim.

Having described the invention, I claim:

In an oiler, a can for containing a lubricating oil having a handle provided with a

finger piece extension, a spout, a packing box on the top of the can through which the spout is movable, a disc on the inner end of the spout providing a plunger, a compressible disc on the periphery of the plunger, said plunger having an opening therein, a spring arm fixed on the under face of the plunger and having an enlarged free end providing a valve for closing the opening in the plunger,
5 a block slideable on the spout, spring means for influencing the block to one position, an upstanding bracket on the can, a lever pivoted to the bracket and having a ring end disposed opposite the finger piece on the handle, and its opposite end offset, a link pivotally secured to the said end, a dog pivotally secured in the block and likewise pivoted to the link and said dog engageable with the spout when the lever is swung in one direction, for the purpose set forth.

In testimony whereof I affix my signature.
PHILIZA FOUNTAINE.
